UNITED STATES PATENT OFFICE.

JOSEPH G. BIXBY, OF DECATUR, ILLINOIS, ASSIGNOR TO BIXBY COMPANY, OF DECATUR, ILLINOIS, A CORPORATION OF ILLINOIS.

BURIAL-SHOE.

1,165,060.

Specification of Letters Patent. Patented Dec. 21, 1915.

Application filed March 6, 1914. Serial No. 822,838.

To all whom it may concern:

Be it known that I, JOSEPH G. BIXBY, a citizen of the United States, a resident of Decatur, in the county of Macon and State 5 of Illinois, have invented new and useful Improvements in Burial-Shoes, of which the following is a specification.

My invention relates to improvements in burial shoes and has for one of its objects 10 the provision of such a shoe which is cheap to manufacture and which has the finished appearance and fit of an expensive shoe.

A further object is the provision of a shoe 15 which readily conforms to the shape of the foot and which may be applied to the foot with facility.

Further objects include the improvement of various details of structure whereby a 20 light, cheap and readily manufactured shoe of finished appearance and good fit is provided.

To the accomplishment of the foregoing and such other objects as may hereinafter appear, my invention consists in the construction, combination and arrangement of 25 parts hereinafter described and then sought to be defined in the appended claims, reference being made to the accompanying drawings, forming a part hereof and which illustrate a preferred embodiment of my invention, it being understood however, that various changes may be made in practice 30 without digressing from my inventive idea.

In the drawings, Figure 1 represents a 35 perspective view of a completed shoe constructed according to my invention, parts being broken away and shown in dotted lines to facilitate the disclosure. Fig. 2 is a perspective view looking down upon the 40 completed shoe, the lining being thrown up. Fig. 3 is a rear end elevation to show the heel construction. Fig. 4 is a detail perspective of the heel, parts being broken away to facilitate the disclosure. Fig. 5 is a 45 perspective view of the base or foundation of the shoe. Fig. 6 is a perspective view looking at the bottom of the heel portion of said base or foundation. Fig. 7 is a vertical section through the toe and vamp portion of 50 the shoe, the parts being somewhat exaggerated.

In shoes of this character it is desirable 55 that they conform to the shape and size of the foot, that they be so constructed as to be capable of considerable yielding and ex-

pansion to permit their ready application to the foot. It is also a material desideratum that such shoes be light and cheap, yet be finished and expensive in appearance. My invention provides a shoe which 60 completely fulfills these and other requirements.

Referring now to the drawings, the numeral 1 designates the base or foundation of the shoe. This is formed of a suitable plastic or fabric, such as buckram, this 65 material being stiff, but capable of being molded over a last or other form when dampened and regaining its normal stiffness when dry. This base or foundation 1 is formed as shown in Fig. 5 having the 70 vamp portion cut out as at 2, but leaving the toe portion 3, side edges 4 and rear portion 5, the latter extending to the heel 6. The back of this heel portion is centrally split as at 7 and the rear part of the sole portion 75 of said base or foundation is split or cut, as at 8, said split or cut taking the form of a curve conforming or corresponding to the curve of the heel. The two lateral splits or cuts 9 are provided, extending from the split 80 or cut 8 to the side of the sole portion as shown. This is for the purpose of permitting portions of the heel to be bent as indicated in Fig. 6 and as will be explained more fully hereinafter. A suitable covering 85 10 for this base or foundation is provided, giving it the form of an ordinary shoe. This covering is of any suitable material, cloth, silk, satin, leather, patent or otherwise, oil cloth and the like, and is held in 90 place by cementing or pasting the lower edge thereof to the sole 11 between the sole and the base or foundation 1. This sole 11 is formed of any suitable flexible material such as felt and has a bead 12 formed on its 95 edge. This bead is provided by securing the flexible binding 13 thereto, a cord 14 running through said binding along the edge of the sole as shown. As shown this binding is secured to the inside of the sole forming, 100 what may be termed, a counter-sunk construction. The purpose of this construction is to securely hold the covering material in place on the base or foundation and to do this with the minimum amount of covering 105 material. As shown in Fig. 7, this covering material 10 merely extends to a point or rather line within the bead, the sole being pasted or cemented thereover. This reduces materially the cost of the shoe in that such 110

a construction necessitates the use of a minimum amount of covering material, the counter-sunk construction preventing it from pulling out. The appearance of the 5 shoe is bettered as the covering material can be lasted more readily over the base or foundation and will not break, crack or wrinkle as would be the case if the covering material extended between the sole and base or foundation for a considerable distance. 10 A suitable lining 15 is secured to the covering material, as by stitching or otherwise, to cover the inside of the base or foundation.

Attention is now directed to the heel portion of the shoe, and particularly to the provision made so that the shoe will fit a foot varying slightly from the standard sizes and so that the shoe may be more readily applied. These advantages are provided for by having the heel portion split and the separated parts held by means of a resilient connection. Considering Figs. 3 and 6 and the description of the cuts or splits 7, 8 and 9, it is seen that parts of the heel portion are foldable or bendable along vertical lines extending from the cuts or splits 9. The heel 16 is secured to the sole and base or foundation by suitable fastening means, such as tacks, which pass through the 20 spacing member 17 of paste-board or other suitable material. As shown, this member 17 provides a space 18 to receive the lateral portions 9' of the bendable heel portions. These heel portions are yieldingly held together by resilient means such as the elastic 25 19, passing through loops 20 on the inside of the heel portions of the base or foundation and extending between the spacing member 17 and the sole portion of the base or foundation, where the ends are secured. 30

It is to be noted that the shoe shown is open like a pump, this being for the purpose of facilitating the application of the shoe to the foot. In order to give the finished appearance necessary for discerning purchasers, I provide the shield or false front 21 which is provided with eyelets 22 and covers the instep portion of the foot, being secured to the edge of the covering material in any suitable manner, as for instance by stitching, as at 23. The base of 45 this shoe is formed of a suitable stiffened material causing the shoe to hold its shape. By having the stiff material removed from the vamp portion of the shoe, it readily conforms to the shape of the ball of the foot insuring a good fit. The side edges 4 of the base or foundation as well as the shank portion thereof, brace the covering material so that the shoe stands up well and retains its shape. The toe portion 3 holds that portion 50 of the shoe in shape and the beaded sole retains the covering material. The hinged heel portions are advantageous in providing 55 for variation of size and assisting in ready

application of the shoe. The material of which the shoe is made is cheap and light, yet the structure is sufficiently strong to withstand the usage to which it is subjected. It is to be noted that the shield or false front 21 is hinged to or bendable on the body portion of the shoe as indicated in Fig. 1. This is for the purpose of having the shoe fit feet having different heights of instep, as is well understood. 75

What I claim is:—

1. A burial shoe having a base or foundation formed of stiff material and a covering or finishing material thereover, said base or foundation extending the full length of the 80 shoe and having substantially no vamp portion so as to permit the shoe to readily conform to the shape of the ball of the foot.
2. A burial shoe having a base or foundation formed of stiff material and a covering 85 or finishing material thereover, said base or foundation having substantially no vamp portion so as to permit the shoe to readily conform to the shape of the ball of the foot, and said base or foundation having a yielding counter construction so as to permit the shoe to adapt itself to variations in the size of feet.
3. In combination, in a burial shoe, a stiff 90 base or foundation having a sole portion, a covering and finishing material therefor, and a sole member having a bead provided on the edge of its upper surface, said sole being secured to said base or foundation with the bead conforming to the shape of 95 the sole portion thereof.
4. In combination, in a burial shoe, a stiff base or foundation having a sole portion, a covering and finishing material therefor, and a sole member having a bead provided 100 on the edge of its upper surface, said sole being secured to said base or foundation with the bead conforming to the shape of the sole portion thereof, said bead being formed by a doubled flexible binding and a 105 cord in the loop thereof.
5. In a burial shoe, a stiff base or foundation, a covering and finishing material therefor, said base or foundation being split at the heel to provide separable counters, the 110 end portions of said counters being bendable relatively to said base or foundation, loops on the inside of said counters, and resilient means passing through said loops and normally holding said counters together. 115
6. In a burial shoe, a stiff base or foundation of shoe shape, a covering and finishing material thereover, a sole secured thereto, a spacing member secured to the inside of the sole portion of said base or foundation at 120 the heel, to form a space between the sole and said spacing member, the heel portion of said base or foundation being split so as to provide separable counters having extensions or flange members adapted to fit in said 125 130

space and means for normally holding said counters together.

7. In a burial shoe, a stiff base or foundation of shoe shape, a covering and finishing material thereover, a sole secured thereto, a spacing member secured to the inside of the sole portion of said base or foundation at the heel, to form a space between the sole and said spacing member, the sole portion of said base or foundation being cut on a curve corresponding to the curve of the heel at a slight distance from the edge thereof, the heel portion of said base or foundation being cut vertically, said last mentioned cut extending to said curved cut, and said sole portion having short lateral cuts extending from said curved cut to the edge of the sole portion of said base or foundation, said cuts providing separable counters bendable on the base or foundation and having extensions or flange members to fit in said space, and means for normally holding said counters together.

8. In a burial shoe, a base or foundation having a sole portion, covering material therefor, a sole member secured thereto, a spacing member in the heel portion of said base or foundation providing a space between the sole member and said spacing

member, a heel secured thereto, said base or foundation having separable counters having portions adapted to fit said space, and resilient means for normally holding said counters together.

9. In a burial shoe, a body portion, sole and heel, said body portion being cut low in the vamp portion and left open simulating a "pump" in appearance, and a shield or false front having eyelets secured to the front upper edge of said low cut portion, whereby the appearance of a complete shoe is given.

10. In a burial shoe, a body portion, sole and heel, said body portion being cut low in the vamp portion and left open simulating a pump in appearance, and a shield or false front secured to the front upper edge of said low cut portion whereby the appearance of a complete shoe is given, said shield or false front being so secured as to be hinged to or bendable on the body portion so as to fit insteps of different heights.

In testimony whereof I affix my signature in the presence of two subscribing witnesses.

JOSEPH G. BIXBY.
